(57) **CLAIM**

Int. Reg. Date: **May 12, 2021**

The ornamental design for a wireless earphone, as shown and described.

Int. Reg. Pub. Date: **Nov. 12, 2021**

(30) **Foreign Application Priority Data**

DESCRIPTION

Dec. 8, 2020 (KR) 30-2020-0060354

1. Wireless earphone

(51) LOC (14) Cl. **14-01**

1.1 : Perspective

(52) U.S. Cl.

1.2 : Front

USPC **D14/223**

1.3 : Back

(58) **Field of Classification Search**

1.4 : Left

USPC D14/223, 205; D13/108; D24/174;
128/864-866; 381/380-381, 322, 328

1.5 : Right

CPC H04R 1/10; H04R 25/00; H04R 25/02;

1.6 : Top

1.7 : Bottom

1.8 : Reference

(Continued)

Reproduction 1.8 is another view showing the subject design is mounted on the cradle with charging pad for wireless earphones; the broken line showing of the cradle with charging pad for wireless earphones is provided for the purpose of illustrating environmental structure and form no part of the claimed design.

1 Claim, 8 Drawing Sheets
